UNITED STATES PATENT OFFICE.

ROSS TURNER, OF SALEM, MASSACHUSETTS.

DESIGN FOR A SPOON.

SPECIFICATION forming part of Design No. 22,994, dated January 2, 1894.

Application filed October 7, 1893. Serial No. 487,522. Term of patent 7 years.

To all whom it may concern:

Be it known that I, ROSS TURNER, a citizen of the United States, residing at Salem, in the county of Essex and State of Massachusetts, 5 have invented a certain new and useful Design for Handles for Spoons, of which the following is a description.

My invention relates to a new and original design for spoon handles, and consists in the 10 configuration and ornamentation of the same as will be hereinafter fully described and claimed.

In the accompanying drawing forming a 15 part of this specification, the figure is a front or face view of a spoon handle made in accordance with my design.

The extremity or end of the handle consists of a ship E representing a Spanish galleon having its sails set. Connecting the ship and

the bowl A is an ornamental handle formed 20 of two dolphins B, the heads of which are attached to the bowl. In the space between the dolphins is placed the representation of a sea shell surmounting which and embracing the tails of the dolphins is a field of filigree work 25 D representing sea weed, in the branches of which rests the ship E.

What I claim is—

The design for spoon handles herein shown and described. 30

In testimony whereof I have signed my name to this specification, in the presence of two subscribing witnesses, on this 3d day of October, 1893.

ROSS TURNER.
